UNITED STATES PATENT OFFICE.

RAYMOND N. EHRHART, OF JEANNETTE, PENNSYLVANIA, ASSIGNOR TO ELLIOTT COMPANY, OF PITTSBURGH, PENNSYLVANIA, A CORPORATION OF PENNSYLVANIA.

SURFACE CONDENSER.

Application filed January 10, 1921. Serial No. 436,052.

Figure 1 is a vertical cross section of a surface condenser embodying my invention, the view being partly conventional;

Figure 2 is a comparative diagram illustrating one of the advantages of my invention;

Figure 3 is a longitudinal vertical section of a condenser embodying the invention.

My invention has relation to surface condensers, and is designed to improve the efficiency of such condensers, particularly in the larger sizes thereof.

As a general rule, apparatus used in the generation of power or in connection therewith increase in efficiency as the size increases. This is particularly true with generating apparatus, such as steam turbines, engines, etc. Surface condensers, which condense the steam from engines or turbines, however, have a tendency to decrease in efficiency as the size increases. In the ordinary construction of such condensers as have heretofore been used, the cylindrical shell of the condenser is more or less completely filled with a bank or nest of tubes through which water is circulated, the steam flowing through the shell around the tubes downwardly from a steam inlet at the top, the air and other non-condensable gases being taken off at a point at or near the bottom of the condenser. It will be readily seen that as the diameter of the condenser increases, the length of the flow path through the banks of tubes also increases, and as the steam has to traverse the entire nest of tubes, the losses in pressure would increase from the steam inlet of the condenser to the point of air offtake, in accordance with the increase in the length of the flow path. The result is that there is considerably less loss in pressure in a small condenser than in a large one. In other words, if the same vacuum is maintained at the air outlets of both large and small condensers, a better vacuum will be maintained in the steam inlet of the small condenser, with the proportions of loadings the same, since there will be less pressure absorbed in flowing over the relatively short flow path in the smaller condenser as compared with the longer flow path in the larger condenser.

In order that the condenser may have the greatest efficiency, the area at different points in the flow path should gradually diminish from the steam inlet to the point of air off-

take, so that relatively the same velocity of flow is kept up throughout the flow zone of the condenser. This is not possible in the ordinary condensers heretofore used, in which the maximum area is at the central horizontal plane of the condenser and diminishes in both directions from such plane. The result is that the curve representing the areas of the flow path in the direction of the flow through such condenser has substantially the form shown by dotted line *a—a* in Figure 2; whereas for the greatest efficiency, this curve should be represented by the line *b—b* in Figure 2. It is possible to modify the line *a—a* considerably by cutting steam lanes through the upper portion of the condenser and by crowding the tubes very close together in the lower portion of the condenser; but even with these changes, the desired gradation of area is only approximate.

The object of my invention is to provide a construction particularly applicable to large condensers and by means of which the efficiency can be maintained in the above respects, notwithstanding the increase in size.

In carrying out my invention, I arrange the tubes in an upper nest or bank 2, of substantially semicircular form in cross section, and a lower nest or bank 3. Baffles 4 are provided which separate the lower nest or bank into two approximately triangular sections, 85 these baffles forming a flow passage 5 for the air and other non-condensable gases from the tubes of the upper nest down between the two sections of the tubes of the lower nest. Preferably, these baffles terminate at a point 90 somewhat above the lowest tubes of the lower nest. 6 designates the usual offtake for air and other non-condensable gases.

The baffles 4 are preferably oppositely inclined, as shown, whereby condensate from the upper nest will pass therefrom into a chamber in open communication with the vapor inlet of the condenser.

It will be noted that the tubes of the upper nest are so arranged that there is a flow space or chamber 7, downwardly around each side of this nest, around the outer edges of the horizontal portions of the baffles 4, and in open communication with the vapor inlet of the condenser whereby steam can flow from both sides in parallel through the upper nest and through the two sections of the lower nest. In this manner, not only is the flow path through each nest greatly shortened, but the area of flow in each nest is substan-

tially as represented by the line *b*—*b* in Figure 2.

I preferably provide for a water circulation through the tubes of the condenser in which the water first flows from the inlet and through the two course nest of tubes to the rear end of the condenser, coming back through the upper nest to the outlet 8.

The advantages of my invention will be readily understood by those familiar with the operation of condensers of this type, since it greatly increases the size to which such condensers may be constructed and operated in an efficient manner.

15 I claim:

1. A surface condenser having a steam inlet and an upper and a lower nest of tubes, said condenser having a chamber for admitting fluid directly from the steam inlet to substantially the whole of that portion of the perimeter including the sides and top of the tube nest facing the steam inlet, and inclined baffles intermediate said tube nests, said tube nests being separated by a substantial horizontally extending space, substantially as described.

2. A surface condenser having two nests of tubes, one substantially semi-circular and the other comprising two substantially triangular sections with a steam passage between the nests and between the substantially triangular sections, substantially as described.

3. A surface condenser having two nests of tubes with a substantial space between them in open communication with the steam space of the condenser, means for directing condensate from the upper nest across said space, and a walled conduit for causing air and non-condensable gases withdrawn from both nests to flow over tubes in the nest through which water is first circulated, substantially as described.

4. A surface condenser having a steam inlet and a plurality of tube nests, said condenser having a chamber for admitting fluid direct from the steam inlet to substantially the whole of the portion of the perimeter including the sides and top of one of said nests facing the steam inlet, and downwardly and outwardly inclined baffles arranged to form separate flow paths for the different nests, and providing an air offtake therebetween.

5. In a condenser, nests of tubes therein, there being a substantial space between said nests, a flow conduit for conveying fluid to a point adjacent the flow terminus of one of said nests, and a gas off-take, non-condensable gases from said conduit and from said last mentioned nest traversing a portion of said last mentioned tube nest before entering said off-take, substantially as described.

6. In a condenser, a top tube nest, a bottom tube nest, there being a substantial space between said nests, and a conduit for fluid terminating adjacent the end of the condensing

zone in said bottom nest, there being a space at the lower portion of said bottom nest through which condensable vapors flow, fluid from said conduit being adapted to traverse said space, substantially as described.

7. In a condenser, a condenser shell, nests of tubes in which fluid flows substantially from top to bottom of said nests, there being a substantial space between said nests, and a conduit for conveying and discharging fluid adjacent the bottom of the lowermost nest in the condenser, substantially as described.

8. In a surface condenser, a shell, an upper and lower nest of tubes, baffles under the upper nest of tubes terminating in a walled conduit leading from the upper nest to the lower nest, there being a chamber in said shell in open communication with the vapor inlet of the condenser, and said baffles being inclined to cause a portion of the condensate from said upper nest to flow to said chamber, substantially as described.

9. In a surface condenser, a shell having an inlet and a flow terminus adjacent the bottom of the shell, a nest of tubes, there being means for conducting fluid from said inlet to a point beneath said nest of tubes, means for conducting condensate from said nest of tubes in such manner that it will flow through said fluid, and a common gas off-take adjacent the bottom of the condenser, a portion of the non-condensable gases from the fluid traversing the tubes adjacent the lower region of the condenser combining with and being withdrawn with the non-condensable gases from the upper region of the condenser through said off-take, substantially as described.

10. In a surface condenser having an inlet for steam and a flow terminus adjacent the bottom thereof and provided with a chamber in communication with the steam inlet, tubes, and means for causing the condensate to flow through said chamber in direct communication with the steam from said inlet, the vapor and non-condensable gases from said chamber traversing a portion of the tubes adjacent the flow terminus, substantially as described.

11. In a surface condenser, a shell having a steam inlet, a tube nest having a flow terminus adjacent the bottom of the shell, there being a chamber in said shell in communication with said inlet, and means for causing condensate to flow through said chamber, vapor and noncondensable gases from said chamber and from the upper portion of the condenser traversing that portion of the condenser adjacent the flow terminus, substantially as described.

12. In a surface condenser having an inlet for steam and a flow terminus adjacent the bottom thereof and provided with a chamber in communication with the steam inlet, tubes, and means for causing condensate to flow through said chamber in direct communica-

tion with the steam from said inlet, the vapor and non-condensable gases from said chamber traversing a portion of the tubes adjacent the flow terminus, said condenser having a walled 5 passage leading through the tubes to a point adjacent the flow terminus, substantially as described.

13. In a surface condenser, two nests of tubes having a substantial space between 10 them in open communication with the steam

space of the condenser, means for passing cooling water through the tube nests in series, and a walled conduit for causing air and non-condensable gases withdrawn from one nest to flow over tubes in the nest through 15 which water is first circulated, substantially as described.

In testimony whereof, I have hereunto set my hand.

RAYMOND N. EHRHART.
